UNITED STATES PATENT OFFICE.

CHARLES M. MORRISON, OF VIROQUA, WISCONSIN.

NAIL-EXTRACTOR.

SPECIFICATION forming part of Letters Patent No. 595,644, dated December 14, 1897.

Application filed April 29, 1897. Serial No. 634,465. (No model.)

To all whom it may concern:

Be it known that I, CHARLES M. MORRISON, a citizen of the United States, residing at Viroqua, in the county of Vernon and State of Wisconsin, have invented certain new and useful Improvements in Nail-Extractors; and I do hereby declare the following to be a full, clear, and exact description of the invention, such as will enable others skilled in the art to which it appertains to make and use the same.

My invention relates to a combined nail-extractor and staple-drawer which may be so adjusted as to draw or extract nails or staples, as may be desired.

15 The invention consists, essentially, in a lever or bar having a central recess or bore at its upper end, a hammer provided with guide-rods fitting in said recess and formed at the lower end with a curved point, and an S-shaped jaw bifurcated at one end, forming two claws, and the other end formed with a single point and provided with two holes to receive a pivot-pin by which it may be pivotally adjusted to said lever-bar to enable 25 it to be used as a nail-extractor or staple-drawer, as hereinafter fully described and claimed.

In the accompanying drawings, Figure 1 is a perspective view of a tool constructed in 30 accordance with my invention, showing the same as used for drawing a staple. Fig. 2 is a longitudinal sectional view of the same. Fig. 3 is a detail perspective showing the device adjusted for use as a nail-extractor.

35 In the said drawings the reference - numeral 1 designates a lever-bar formed in the upper end with a central recess or bore 2. Located in this recess are guide-arms 3, consisting of a metal rod bent over centrally, as 40 seen in Fig. 2, and the ends connected with a hammer 4. A pin 5, passing transversely through said bar, holds said arms in place. The lower end of said lever-bar is provided with a shank 6, the end or extremity of which 45 is formed into a curved point 7.

The numeral 8 designates a metal jaw made in the shape of an S and bifurcated at one end, forming two claws 9. The other end is

formed with a blunt point 10. This jaw at opposite sides of its center is formed with 50 two holes 12 and 13 for the passage of a pivot-pin 14, which also passes through a hole in the shank 6.

In practice, when the device is to be used as a staple-drawer, the jaw is pivotally connected with the shank 6 by passing the pivot-pin through the hole 13. By now grasping the staple between the points 7 and 10 and using the bar 1 as a lever the staple can be readily withdrawn. To use the device as a 60 nail-extractor, the jaw is reversed, the pivot-pin being passed through the hole 12 and the claws engaged with the head of the nail, the hammer being driven down onto the top of the bar 1, so as to force the claws 9 and point 65 7 under the head of the nail.

Having thus fully described my invention, what I claim is—

1. In a combined nail-extractor and staple-drawer, the combination with the lever-bar 70 having a curved lower end, of the adjustable and reversible S-shaped jaw bifurcated at one end forming two claws, and the other end formed with a single point and formed with two pivot-holes at opposite sides of the 75 center and the pivot-pin connecting said jaw with the lever-bar, substantially as described.

2. The combination with the lever-bar, having a central recess at the upper end, the transverse pin, the hammer, the guide-arms 80 consisting of a metal rod bent at the center and having the ends secured to said hammer and the lower end of said bar formed with a curved point, of the S-shaped jaw bifurcated at one end forming two clamps, and the other 85 end formed with a solid point, and said jaw formed with two holes at opposite sides of the center and the pivot-pin connecting said jaw with the lever-bar, substantially as described.

In testimony whereof I affix my signature 90 in presence of two witnesses.

CHARLES M. MORRISON.
